UNITED STATES PATENT OFFICE.

ARTHUR O. ERICKSON, OF GREENWOOD, NEW YORK.

ANTIKICKING DEVICE FOR COWS.

1,163,867.

Specification of Letters Patent. Patented Jan. 18, 1916.

Application filed November 9, 1914. Serial No. 871,143.

To all whom it may concern:

Be it known that I, ARTHUR O. ERICKSON, a citizen of the United States, residing at Greenwood, in the county of Steuben, State of New York, have invented certain new and useful Improvements in Antikicking Devices for Cows; and I do hereby declare the following to be a full, clear, and exact description of the invention, such as will enable others skilled in the art to which it appertains, to make and use the same.

This invention relates to anti-kicking devices for cows, and more particularly to an article which is adapted for application to the rear leg of a cow whereby to prevent bending of the hock joint as is necessary when the animal attempts to kick.

An object of the invention resides in the provision of a simple and durable appliance of the above character in which there is embodied a novel form of mechanism whereby the same may be quickly and easily applied to and secured in position on the leg of the animal.

With the above and other objects of similar nature in view, the invention consists in the construction, combination and arrangement of parts, set forth in and falling within the scope of the appended claim.

In the drawing:—Figure 1 is a side elevational view illustrating the rear portion of a cow with the invention in applied position. Fig. 2 is a plan view of the device showing in dotted lines the position of the animal's leg. Fig. 3 is a front view, and Fig. 4 is a detail perspective view of the securing means for the device. Fig. 5 is a detail sectional view taken on the line 5—5 of Fig. 2 with the latch in inoperative position.

Referring now more particularly to the drawing, the device is shown as comprising a rod A of any desired material, the intermediate portion 10 of which is shaped to conform to the outside curvature of the rear leg of a cow, with the ends 11 and 12 flattened and curved laterally therefrom whereby to provide a pair of suitable leg receiving portions to respectively engage the front of the leg above and below the hock joint.

Secured to the intermediate portion 10 of the rod and extending rearwardly therefrom is the stationary jaw 13 of the clamping member B of the device. Hingedly connected as at 14 to the free end of the stationary jaw 13 is the movable jaw 15 of the clamp, said jaws being each outwardly

bowed as at 16 and adapted to receive and tightly clamp the large tendon of the leg above the hock joint whereby to secure the device in applied position. The movable jaw 15 is further provided at its free end with an angularly directed portion 17 in which is disposed an opening 18 for the reception therethrough of a bolt 19.

For operating the clamp B, there is arranged transversely of the outer face of the stationary jaw 13, a wedge-shaped latch plate 20, said plate having formed therein a plurality of notches 21 for the purpose to subsequently appear. Swingly connected with the movable jaw 15 and adapted for movement longitudinally of the wedge plate 20, is a latch member 22, said member being in the form of a substantially U-shaped yoke that embraces the jaws 13 and 15, when in locking position, and is provided at its free end with a curved and sharpened edge 23 for locking engagement in the notches 21 of the plate.

In connecting the yoke 22 with the jaw 15 there is formed on the end thereof opposite from the sharpened edge 23, an inwardly projecting portion 24 having an opening 25 therein for the reception of the bolt 19.

Having now fully described the invention, in applying the device to a cow's leg the member A is engaged thereon in the manner as clearly illustrated in Fig. 1, with the jaws 13 and 15 receiving therebetween the large tendon of the leg above the hock joint. The yoke 22 is then engaged with the bolt 19 and swung to the position shown in Fig. 2 to embrace the jaws of the clamp, the sharpened edge 23 engaging and moving downwardly on the wedge plate 20, to press said jaws tightly about the tendon, and locking in one of the notches 21 when the desired pressure on the leg has been obtained.

What is claimed, is:—

An anti-kicking device for cows, comprising a leg engaging member provided with means to embrace the hind leg of a cow above and below the hock joint, a stationary clamping element secured at one end to said member, and extending rearwardly therefrom, a movable clamping element pivoted at the free end of, and cooperating with the stationary element to retain the device in applied position, a wedge plate arranged transversely of said stationary element and having notches formed therein, and a substantially U-shaped keeper, normally disposed in

the plane of, and embracing said fixed and movable elements, said keeper being swingingly secured at one end to the free end of the movable element, with its other end movable transversely of said stationary element, and adjustably engageable in said notches.

In testimony whereof, I affix my signature, in the presence of two witnesses.

ARTHUR O. ERICKSON.
